CONTROLLING APPARATUS FOR HIGHWAY
CROSSING SIGNALSHarry C. Vantassel, Swissvale, Pa., assignor to
The Union Switch & Signal Company, Swiss-
vale, Pa., a corporation of Pennsylvania

Application April 10, 1935, Serial No. 15,634

8 Claims. (Cl. 246—130)

My invention relates to controlling apparatus for highway crossing signals, that is, to means for the control of signals which are placed at intersections of railways and highways for the purpose of warning users of the highway when a train is approaching.

One feature of my invention is the provision of means which will control a highway crossing signal for a track on which trains move in both directions in such a manner as to stop the operation of the signal after it has been initiated by an approaching train if such train consumes more than a predetermined time interval in approaching the crossing, and which also will again initiate the operation of the signal if the train subsequently approaches the crossing.

I will describe one form of apparatus embodying my invention, and will then point out the novel features thereof in claims.

20 The accompanying drawing is a diagrammatic view illustrating one form of apparatus embodying my invention.

Referring to the drawing, the rails 1 and 1A of a stretch of railway track X are divided by insulated joints 2 into relatively long sections 25 A—B and C—D, which are separated from each other by a relatively short section B—C. Section B—C includes the intersection of the railway and a highway designated by the reference character H. Each section is provided with a track circuit including a track relay designated by the reference character R with a distinguishing suffix connected across the rails 1 and 1A at one end of the section, and a track battery 3 connected across the rails at the other end of the section. The highway crossing H is protected by a signal S of any suitable type such, for example, as a bell or a light signal or a combination of both, which signal is controlled by a signal control relay designated by the reference character K.

The sections A—B and C—D usually will be of such length as to provide adequate warning at the crossing for trains traveling at normal speed, 45 and section B—C usually will be of such length as to provide adequate warning for trains traveling at slow speed.

Associated with each track relay R1 and R3 is 50 a stick relay designated by the reference character P with the same suffix as that used in the reference character for the associated track relay.

Associated with each stick relay P1 and P3 is a 55 timing device, here shown as a thermal relay,

and designated by the reference character T with a suitable distinguishing suffix.

As will be explained hereinafter, the stick relays P1 and P3 are effective to prevent operation of the crossing signal by the relays R1 and 5 R3 when the sections A—B and C—D become occupied by trains receding from the crossing and also are effective in conjunction with the associated thermal relays for discontinuing the operation of the signal if a train moving towards 10 the crossing consumes more than a measured interval of time in the initial control section.

The reference character 4 designates a source of energy which is here shown as a battery.

Each of the thermal relays T1 and T3 is provided with contacts 10 and 14, respectively, which are closed only when the associated relay is in its initial or deenergized condition, and with contacts 12 and 16, respectively, which are closed only when the associated relay attains its operated condition a predetermined time interval 15 after energy is applied to heating elements 17 and 18, respectively.

The signal 3 is controlled only by a back contact 5 of relay K. Signal S, therefore, will be 20 operated when relay K is released and back contact 5 becomes closed.

The signal control relay K is provided with a main control circuit and two auxiliary circuits. The main control circuit passes from battery 4 25 through front contact 11 of relay R1, front contact 15 of relay R3, front contact 6 of relay R2 and relay K to battery 4. The first auxiliary circuit passes from battery 4 through contact 10 of relay T1, front contact 7 of relay P1, and 30 thence over front contact 15 of relay R3 and the same path just traced for the main control circuit. The second auxiliary circuit passes from battery 4 through front contact 11 of relay R1, front contact 21 of relay P3, contact 14 of relay 35 T3 and thence over front contact 6 of relay R2 and the same path just traced for the main control circuit. Signal control relay K, therefore, will become released at all times when relay R2 is released, and also will become released when 40 relays R1 or R3 become released provided the associated stick relays are in their normal deenergized condition.

The thermal relay T1 is provided with a circuit which passes from battery 4 through back 50 contact 9 of track relay R1, the back point of contact 6 of relay P1 and heating element 17 of relay T1 to battery 4. Likewise, the thermal relay T3 is provided with a circuit which passes from battery 4 through back contact 13 of track relay 55

R₃, the back point of contact 8 of relay P₃ and heating element 18 of relay T₃ to battery 4. Relays T₁ and T₃, therefore, will become energized when relays R₁ and R₃, respectively, become released provided the associated stick relays are in their normal deenergized condition.

Each stick relay P₁ and P₃ is provided with two pick-up circuits and one stick circuit. The first pick-up circuit for relay P₁ passes from battery 4 through back contact 19 of relay R₂ and relay P₁ to battery 4. The second pick-up circuit for relay P₁ passes from battery 4 through contact 12 of thermal relay T₁ and relay P₁ to battery 4. The stick circuit for relay P₁ passes from battery 4 through back contact 9 of relay R₁, front point of contact 6 of relay P₁ and relay P₁ to battery 4. The first pick-up circuit for relay P₃ passes from battery 4 through back contact 20 of relay R₂ and relay P₃ to battery 4. The second pick-up circuit for relay P₃ passes from battery 4 through contact 16 of thermal relay T₃ and relay P₃ to battery 4. The stick circuit for relay P₃ passes from battery 4 through back contact 13 of relay R₃, front point of contact 8 of relay P₃ and relay P₃ to battery 4. The stick relays P₁ and P₃, therefore, will become energized when track relay R₂ is released or when the associated thermal relay is in its operated condition, and upon being energized will be maintained in their energized positions when the track relays R₁ and R₃, respectively, are released.

Having thus described the various parts of the apparatus embodying my invention, I will now explain their operation.

Under normal conditions, the track relays R₁, R₂, and R₃ are all energized and the stick relays P₁ and P₃, as well as the thermal relays T₁ and T₃ are all deenergized. I shall now assume that an eastbound train, that is, a train moving toward the right as shown in the drawing, enters section A—B and causes the deenergization of track relay R₁. This opens front contact 11 of relay R₁ which interrupts the main control circuit for the signal control relay K. The deenergization of relay K establishes the signal operating circuit passing through back contact 5 of relay K, thereby causing the signal S to give warning to traffic on the highway H of the approaching train.

I shall next assume that the train stops in section A—B. For example, the train may stop to discharge or receive either passengers or freight. The deenergization of track relay R₁, in addition to initiating the operation of the signal S, will also, through the closing of its back contact 3, establish a circuit over the back point of contact 6 of relay P₁ for heating element 17 of thermal relay T₁. As soon as heating element 17 begins to heat checking contact 18 will become opened and will not become closed again until heating element 17 cools after energy is disconnected.

At the expiration of a given time interval when relay T₁ has attained its operated condition contact 12 will become closed. When contact 12 is closed stick relay P₁ becomes energized so that energy is disconnected from heating element 17. As soon as heating element 17 cools so that checking contact 18 recloses, an auxiliary circuit for relay K, including front contact 7 of relay P₁ and checking contact 18, becomes closed thus energizing signal control relay K so that signal S ceases operation. From the foregoing description, it is readily apparent that thermal relay T₁ must go through a complete cycle of energization and subsequent deenergization in order to interrupt the operation of signal S when the signal

is operating due to the occupancy of section A—B. That is, energy must be applied to heating element 17, contact 12 must close to energize the stick relay so that energy will be removed from heating element 17, and the heating element 17 must cool to permit the reclosing of checking contact 18. Usually, the relay T₁ will be so adjusted that its complete cycle of operation cannot take place during the time required for a train traveling at normal speed to traverse section A—B. The operation of signal S, therefore, will not be discontinued for trains traversing section A—B at normal speed but only in the event such trains stop or otherwise consume in section A—B an interval of time greater than the total operating time of thermal relay T₂.

I shall next assume that the train again proceeds towards the crossing and enters section B—C, thus releasing track relay R₂. Since the main circuit for the control of relay K includes front contact 6 of relay R₂, the signal S will again operate to warn highway traffic of the approaching train and will continue to operate as long as section B—C is occupied. The releasing of relay R₂ will close its back contact 20 so that a pick-up circuit of relay P₃ is established. When relay P₃ picks up, the auxiliary circuit around front contact 15 of relay R₃ is closed so that, when the train enters section C—D and front contact 15 becomes opened, the relay K will not become deenergized. The stick circuit for relay P₃, including the front point of its own contact 8, will be closed when back contact 13 of track relay R₃ becomes closed so that relay P₃ will remain energized while the train is traversing section C—D. The signal S, therefore, is prevented from operating while the train is receding from the crossing although track relay R₃ is released.

While I have not described the operation of the apparatus embodying my invention for a westbound train, it will be seen from the foregoing description that the apparatus functions in a manner similar to that just described for an eastbound train.

Although I have shown apparatus embodying my invention applied to a single track, it is readily apparent to those skilled in the art that, if desired, the relay K may be controlled from more than one track by apparatus exactly similar to that shown for track X.

The apparatus embodying my invention, therefore, provides a simple and reliable means for operating a highway crossing signal in which excessive operation of the signal is prevented in the event that an approaching train initiates the operation of the signal and then does not proceed immediately over the crossing. Furthermore, my invention provides for a second operation of the signal when such train subsequently approaches the crossing.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a stretch of railway track intersected by a highway, a signal for controlling traffic over said highway at such intersection, means effective to initiate the operation of said signal when railway traffic moving towards the intersection occupies certain zones, means effec-

5 tive to discontinue the operation of said signal a measured time interval after such initiation, and means effective to cause the operation of said signal when railway traffic moving in either direction occupies a particular zone adjacent the intersection.

2. In combination, a stretch of railway track divided into a first section and a third section separated from each other by a second section 10 intersected by a highway, a signal for controlling traffic over said highway at such intersection, a signal control relay, a first track relay associated with said first section for controlling said signal control relay, a second track relay associated 15 with said second section for controlling said signal control relay, a third track relay associated with said third section for controlling said signal control relay, means for causing said first and said third track relays to be effective for controlling said signal control relay for traffic moving only towards said highway, and means for removing said signal control relay from control 20 by said first and third track relays a predetermined time interval after such track relays become effective for controlling said signal control relay.

3. In combination, a stretch of railway track divided into a first section and a second section separated from said first section by another section 30 intersected by a highway, a signal for controlling traffic over said highway at such intersection, a first track relay associated with said first section for controlling said signal for railway traffic moving over said stretch in one direction, a second track relay associated with said second section for controlling said signal for railway traffic moving over said stretch in an opposite direction, another track relay associated with said other section for controlling said signal for railway traffic moving over said stretch in either direction, two thermal relays one associated with each of said first and second sections, two stick relays one associated with each of said first and second sections, means responsive to 45 traffic conditions in said first and said other section for controlling the thermal relay and the stick relay associated with the first section, and means responsive to traffic conditions in said second and said other section for controlling the thermal relay and the stick relay associated with the second section.

4. In combination, a stretch of railway track divided into three sections, a track relay for each section, two thermal relays one associated with 55 each of two of said track relays, two stick relays one associated with each of such two track relays, a signal, a signal control relay, a first circuit for said signal control relay including a front contact of each track relay, a second circuit for said signal control relay including a contact of the thermal relay and a front contact of the stick relay associated with one of said track relays, and a third circuit for said signal control relay including a contact of the thermal relay and a 60 front contact of the stick relay associated with the other of said track relays.

5. In combination, a stretch of railway track including an intersection with a highway, a first track section and a second track section included 70 in said stretch and successively occupied by a train approaching said intersection, a highway crossing signal located at said intersection, a normally energized signal control relay effective when deenergized to cause the operation of said signal, a track circuit including a track relay for each sec-

tion, means governed by the track relay for the first section effective to deenergize said signal control relay when such track relay becomes released by a train approaching the intersection, means effective to energize said signal control 5 relay a predetermined time interval after the release of the track relay for the first section, and means governed by the track relay for the second section for again deenergizing said signal control relay when such track relay becomes released. 10

6. In combination, a stretch of railway track including an intersection with a highway, a first track section and a second track section included in said stretch and successively occupied by a train approaching said intersection, a highway 15 crossing signal located at said intersection, a normally energized signal control relay effective when deenergized to cause the operation of said signal, a track circuit including a track relay for each section, means effective to deenergize said 20 signal control relay when the track relay for the first section becomes released by a train approaching the intersection, a normally deenergized stick relay, a timing device having an initial condition and an operated condition, means effective to initiate the operation of said timing device when the track relay for the first section becomes released provided said stick relay is then in its deenergized condition, means effective to energize said stick 25 relay when said timing device attains its operated 30 condition, means then effective to hold said stick relay in its energized condition as long as the track relay for said first section remains released, means effective to energize said signal control relay when said stick relay is in its energized condition provided said timing device is then in its initial condition, and means governed by the track 35 relay for the second section for again deenergizing said signal control relay when such track relay becomes released. 40

7. In combination, a stretch of railway track including an intersection with a highway, a first track section and a second track section included in said stretch and successively occupied by a train approaching said intersection, a highway crossing signal located at said intersection, a normally energized signal control relay effective when deenergized to cause the operation of said signal, a track circuit including a track relay for each section, a normally deenergized stick relay, a timing 45 device having an initial condition and an operated condition, means effective to initiate the operation of said timing device when the track relay for the first section becomes released provided said stick relay is then in its deenergized condition, means effective to energize said stick relay when said timing device attains its operated condition, means then effective to hold said stick relay in its operated condition as long as the track relay for said first section remains released, a circuit for 50 said signal control relay including a front contact of the track relay for the first section and a front contact of the track relay for the second section, and a branch path connected around the front contact of the track relay for said first section including a front contact of said stick relay and a contact closed only when said timing device is 55 in its initial condition. 60

8. In combination, a stretch of railway track including an intersection with a highway, a first 70 track section and a second track section included in said stretch and successively occupied by a train approaching said intersection, a highway crossing signal located at said intersection, a normally energized signal control relay effective when 75

deenergized to cause the operation of said signal, a track circuit including a track relay for each section, a normally deenergized directional relay which becomes energized a predetermined interval of time after the track relay for the first section becomes released or when the track relay for the second section becomes released, means effective when said directional relay is in its energized condition to hold such relay in that condition as

long as the track relay for the first section is released, means for deenergizing said signal control relay when the track relay for the first section becomes released provided said directional relay is then deenergized, and means for deenergizing said signal control relay when the track relay for the second section becomes released. 5
